John W. Flansburgh, of Philadelphia, Penn.

- Assn. No -

North, Chase and North, of Philadelphia, Penn

Letters Patent No. 1792, dated June 30th 1863.

The schedule referred to in these Letters Patent and making part of the same.

To all whom it may concern:

Be it known that I, John W. Flansburgh, of the City of Philadelphia, in the State of Pennsylvania, have invented or produced a new and original Design for Stove Plates, and I do hereby declare that the following is a full and exact description of the same, reference being had to the accompanying drawings, marked "sheet 1" and "sheet 2", and making a part of this specification, in which figures 1 and 2 are the oven doors of the stove.

Figure 3. one of the front fire doors;

Figure 4. the end fire door or panel;

Figure 5. the top plate, in section; and

Figure 6. the ash pit plate, in section.

The oven doors have a raised ornamental figure in their centres, and are each bounded by a raised moulding a. a. as represented in the figures, a transverse section thereof being also shown by the dotted lines 1. 1. The end fire door or panel, figure 4., and the front fire door, figure 3. have each a raised ornamental figure in their centres, and are bounded by a raised moulding a. a. of the same form and transverse section as that of the oven doors, as seen in the drawings.

The top plate figure 5. is bounded by a depressed

Dec. 1792

moulding b. b. whose transverse section is indicated by the dotted line K.

The wash plate figure b. is bounded by a raised moulding c. whose transverse section is indicated by the dotted line S. as seen in the drawing.

That I claim as my invention or production, and desire to secure by letters patent, as a Design for stove plates, is the plates and ornaments as shown and described.
